UNITED STATES PATENT OFFICE.

JOHN S. GULLBORG AND CLARENCE S. ONGMAN, OF CHICAGO, ILLINOIS.

HOUSE HEATER.

Application filed February 18, 1927. Serial No. 169,316.

This invention relates to heating devices, and more particularly to a heater particularly adapted for house use.

Our invention relates to that class of heaters which form in themselves a complete heating unit and are provided with radiating surfaces of appreciable area for radiating into the room the heat generated in such unit. The common example of such a unit is the gas-steam radiators in which water in the radiator is heated by a suitable type of gas heater and is thereby converted into steam. This radiator, while efficient as a heater, is objectionable in several respects. It is not portable in the sense that it can be readily moved as desired from one position to another, since it is necessary to connect the gas heater to a supply line. It is also objectionable in that the fumes from the gas heater enter the room which in some instances, as where the heater gives off carbon-monoxide gas, is very dangerous. There is also a very appreciable portion of the heat from the gas burner which is lost or dissipated without serving any useful purpose in heating the water or steam within the radiator resulting in reduced efficiency as compared to a device of this general character in which this loss of heat from the burner or heating element is eliminated.

In our heating device the above noted objection to the gas-steam radiator is avoided in that we employ heating elements which are disposed within the radiator structure so as to be surrounded by the liquid or fluid within the radiator for absorbing the heat and transmitting it to the walls of the radiator. A further important advantage of our heater is its portability which permits it to be readily moved from place to place, which is frequently an important consideration. The heating elements which we employ are preferably in the form of electrical resistances and are so mounted as to effectually eliminate all possibility of the escape of any fumes into the room. We also preferably provide suitable means for causing a current of air to flow over the radiator structure to absorb the heat radiated therefrom and distribute it throughout the room. Further objects and advantages will appear from the detailed description.

In the drawings:—

Figure 1 is a central vertical section

through a heating device taken from end to 55 end thereof;

Fig. 2 is a central vertical transverse section, parts being shown in elevation;

Fig. 3 is a central horizontal sectional view through the heating device parts being 60 shown in elevation;

Fig. 4 is a fragmentary sectional view through one of the tubes and its associated fins; and

Fig. 5 is a diagram of the switch and connections of the motor and the heating elements.

The radiator includes the hollow base 1 of generally rectangular shape in vertical and horizontal section. The lower end of this 70 base is closed by a bottom plate 2 which fits into a suitable groove or rabbet provided for this purpose in the thickened portion or flange 3 of the base. The base is supported by feet 4 at the corners thereof, these feet 75 being provided at their upper ends with horizontal and vertical flanges 5 and 6, respectively, disposed to engage beneath and about the rounded corner portions of the base.

A header 7 of generally rectangular shape 80 in vertical and horizontal section is disposed above base 1 and is secured thereto by tubes 8, the ends of which extend through suitable openings in the bottom wall of the header and the top wall of the base and are expanded and beaded over in a known manner to form a fluid tight closure therewith.

These tubes are provided with radiating fins 9 secured thereon. These fins may be flat as in Figure 2 or may be corrugated as 90 in Figure 4 to increase their radiating surfaces. The base and the header are also connected by a central brace 10 of cruciform cross-section which is provided at its ends with securing flanges 11 seating upon blocks 95 12 and 13 projecting from the top wall of the base and the bottom wall of the header, respectively. Securing screws 14 pass through these flanges and thread into the blocks. The brace serves to positively prevent movement of the base and the header toward each other, relieving the tubes of excessive strains, and this brace also provides a support for a fan or blower 15 of known type for directing a current of air 100 through the radiator between the tubes and the fins thereof. The blower 15 is provided with a pulley 16 which is connected by a

cord 17 to pulley 18 secured on the armature shaft of an electric motor 19 secured to the under face of bottom plate 2. A screen or guard 20 of perforated sheet metal 5 extends upwardly from the lower portion of base 1 above the fan and has its upper portion turned inwardly and secured to the header 7. This screen 20 co-acts with the body portion of the radiator to effectually 10 enclose the fan in such manner as to eliminate danger of anyone being injured thereby through carelessness. The screen or guard 20 is preferably open at both ends, as illustrated in Figure 3, to permit ready 15 flow of air to the fan, a large volume of air also flowing to the fan through the perforations of the guard 20. The fan thus acts to direct a large volume of air over and about the tubes and the fins of the radiator 20 structure so as to absorb the heat therefrom and quickly distribute the heat throughout 25 the room or compartment being heated.

The top of header 7 is open and the header is provided, a short distance from its upper 25 edge, with an inwardly projecting flange 21. This flange provides, with flange 22, a groove or rabbet for reception of a closure plate 23 which is removably secured in position by screws 24 passing through the plate and 30 threading into flange 21.

A hood 25 is secured over the upper end of header 7 in any suitable manner, as by means of screws or equivalent means, permitting removal of the hood when desired. This hood 35 carries, at one end, a socket 26 of known type having an associated cable or cord 27 for connection to an outlet or convenience socket, such as are commonly provided in houses, for connecting the socket to the house wiring 40 system. A switch 28 is mounted at the other end of the hood. One pole of the socket member 26 is connected by a wire 29 to the center pin or pivot member 30 of switch 28. An arm 31 extends from pin 30 and is provided 45 with an outer contact 32 and an inner relatively short contact 33. These contacts, as well as the arm 31 and the pin 30, are all of electrical conducting material. The switch structure includes fixed concentric contact strips 33^a and 34 and fixed contacts 35 and 36. Contact 36 is connected by wire 37 to one terminal of one of the heating elements 38, the other terminal of this element being connected by wire 39 to the other pole of socket member 26. Contact strip 34 is connected 50 by wire 40' to one terminal of the other heating element 38, the other terminal of this element being connected by wire 41' to wire 39. Contact strip 33^a is connected by wire 42' to one brush of the motor 19. The other brush of the motor is connected by wire 43' to wire 39. The contact 35 is connected by wire 44' to wire 37. By referring to Figure 5, it will be noted that the switch 55 28 has three operative positions. When the

arm 31 is moved into its first operative position in a clockwise direction, the contacts 32 and 33 are in engagement with contact 35 and contact strip 33^a, respectively. This closes the circuit through motor 19 as well as 70 through the first or left-hand heating element 38. When arm 31 is moved into its second position contacts 32 and 33 are in engagement with contact strips 33^a and 34, respectively. This breaks the circuit through 75 the left hand heating element 38 and closes the circuit through the right hand element. When the arm is moved into its third operative position, contact 32 is in engagement with the contact strip 34 and contact 36, contact 33 remaining in engagement with the contact strip 33^a. This closes the circuit through both of the heating elements to produce the maximum heating effect. In all of the operative positions of arm 31, contact 80 33 remains in engagement or operative relation with strip 33^a maintaining the motor circuit closed. Movement of the arm 31 into the inoperative position illustrated in Figure 5 opens all of the circuits, including the motor circuit, rendering the device inoperative. 90

The heating units 38 are elongated U-shape and the arms 39 of each unit extend through two adjacent tubes 8. The end portions of these arms extend through depressions or 95 cups 40 formed integrally with closure plate 23. These cups or depressions are interiorly threaded for reception of packing nuts 41 which cooperate with the cups 40 to form packing glands for receiving and securing 100 the ends of the arms 39 and forming a fluid tight closure about the same, these packing glands including a suitable packing 42. The units 38 are of known construction and include an outer sheathing or tube of any suitable metal or alloy which will resist the action of the fluid or liquid within the radiator structure. Within this protecting 105 sheathing or tube is mounted a resistance element and a suitable filling of refractory clay, 110 or other suitable material, in which the resistance element is embedded. As the construction of heating elements of this general character are well known in the art, it is not necessary to illustrate the same or describe it 115 in further detail. While we have illustrated but two heating elements and have shown the arms of the respective elements as extending through adjacent tubes 8, it will be understood that any desired number of these elements may be utilized depending largely upon the size of the heating device, and they may be arranged in various relations, though we prefer to arrange these elements in the manner illustrated and described, as this produces a very simple and highly efficient construction. The U-shape of these elements is of advantage in permitting expansion and contraction thereof without subjecting them 120 to dangerous stresses. It is also to be noted 125 130

that the arms 39 are disposed centrally of the tubes 8 and spaced away from the surrounding walls of the tubes, the bight portion of these elements extending below the tubes an appreciable distance into the base 1.

Under ordinary conditions we use water in the radiator structure as the heat transferring medium, though any other liquid or fluid suitable for this purpose may be employed. The water level should be a short distance above the bottom wall of the header 7, sufficient space being left in the header to permit of expansion of the water when heated. To determine the water level, we preferably provide a suitable gauge 43 of known type connecting the header 7 and base 1. The water is poured into the radiator structure through a suitable filling spout 44 provided for this purpose and extending from the header 7. This spout is closed by a removable closure member 45 provided with a safety valve 46 which is adjusted to open at a predetermined pressure, as is known. After the water has been placed in the radiator structure, the circuit through one or both of the heating elements, as desired, is closed. These elements serve to quickly raise the water to a high temperature, thus heating the radiator structure, the radiated heat being removed to a large extent by the air drawn or blown through the structure by the fan or blower 15, which serves to distribute the heat in the manner previously described. The device is set in any suitable position in the room and is connected to a convenient outlet or socket by means of the cord 27 and the usual plug attached thereto. When the device is set adjacent a wall, as under a window, the perforated guard or screen 20 should be placed away from the wall so that the air discharged by the fan or blower through the fins and tubes will flow into the room. It will be understood, however, that the device can be placed in any position desired with perfect safety as the fan is completely enclosed. It will also be understood that the fan can be arranged to blow air through the fins and about the tubes or to blow air through the perforated screen 20, inducing air through the fins and about the tubes, as desired.

To facilitate circulation of the water or other liquid within the radiator structure, we provide circulating tubes 47 similar to tubes 8 and alternating therewith, these circulating tubes establishing communication between the base 1 and the header 7. As the water or other liquid is heated, it flows upwardly through the tubes 8 and about the arms 39 of the heating elements 38 so as to be heated thereby, during its upward travel, to a high temperature. The liquid flows from the upper ends of the tubes 8 into the header 7 where it gives up a portion of its heat and becomes relatively cool, the cool

liquid then flowing downwardly through the tubes 47 and dividing into two streams at the lower end of this tube, one flowing toward one of the tubes 8 and the other toward the other adjacent tube 8. This insures very rapid circulation of the liquid with the result that the radiator structure is quickly raised to a relatively high temperature and is maintained at such temperature so long as the heating elements 38 are in operation.

Under certain conditions instead of using water as the heat transferring medium, we prefer to use some other medium which has a high boiling temperature. We find that paraffin oil is very suitable for this purpose, this oil having a boiling point of 500° F. By employing paraffin oil the radiator structure can be readily raised to a much higher temperature than when water is employed, thus greatly increasing its efficiency and heating capacity. This is very desirable under conditions where it is necessary or preferred to use a structure of small dimensions. When water is employed as the heat transferring medium, it is altogether feasible to construct a heating device of this character of such size and weight as to be readily transported, and the size and weight of the device can be very materially reduced by employing paraffin oil, or any other suitable liquid or fluid as the heat transferring medium.

Whatever heat transferring medium is used, it will be noted that the heating elements are completely immersed in this medium and surrounded thereby, so that the heat generated by such elements is taken up by the heat transferring medium and transferred to the radiator structure. This very effectually eliminates any loss of heat and results in very high heating efficiency. It will also be noted that the heating elements are of such a character and are so completely enclosed that there is no possibility of the escape into the room of objectionable or injurious fumes.

For convenience in assembly and to permit ready insertion and removal of the heating elements, the bottom plate 2 of base 1 is removably secured in position in any suitable or preferred manner, so as to effect a fluid tight closure between this plate and the base. We have shown this plate as secured in position by means of screws 47' passing through the plate and threading into the thickened portion 3 of the base, though any other suitable or preferred means may be employed for this purpose.

To facilitate moving the device from place to place, we provide a handle 48 of suitable type, the end portions of which are secured through loops 49 secured to the top of hood 25. We have illustrated the switch 28 as of the button type and as provided with a head or button 50 secured on the upper end of the

pivot member or pin 30 to facilitate turning thereof. It will be understood, however, that the switch can be of any suitable or preferred construction and provided with any one of several well known means for operating the switch arm.

While we have shown the blower or fan 15 as rotatably mounted on the stub shaft 51 secured in a sleeve 52 of the brace member 10, it will be understood that this fan can be supported in position in any suitable manner.

As above indicated, changes in the construction and arrangement of parts of the 15 invention may be resorted to without departing from the field and scope of the same, and we intend to include all such variations, as fall within the scope of the appended claims, in this application in which the preferred 20 form only of our invention is disclosed.

What we claim is:—

1. In a heating device of the character described, a portable radiator structure for containing a heat absorbing fluid, said structure including a base and a header and tubes connecting the base and header, a closure plate for the top of the header, electrical heating elements extending through the plate and downwardly therefrom through the tubes, and means for securing the heating elements in the plate and for effecting a fluid tight closure between them and the plate.

2. In a heating device of the character described, a portable radiator structure for containing a heat absorbing fluid, said structure including a base and a header and tubes connecting the base and header, a closure plate for the top of the header, electrical heating elements extending through the plate and downwardly therefrom through the tubes, means for securing the heating elements in the plate and for effecting a fluid tight closure between them and the plate, a

hood fitting over the header, and means carried by the hood and having electrical connection with the heating elements for connecting said elements to an electrical circuit and for controlling their respective circuits.

3. In a heating device of the character described, a portable radiator structure for containing a heat absorbing fluid, said structure including a base and a header and tubes connecting the same, said tubes establishing communication between the base and the header for circulation of the fluid, and electrical heating elements of substantially elongated U-shape having their arms extending through adjacent tubes.

4. In a heating device of the character described, a radiator structure adapted to contain a heat absorbing fluid, said structure including a base and a header and tubes establishing communication between said header and the base, heating elements extending through the tubes, and circulating tubes between the tubes receiving the heating elements and establishing communication between the header and the base.

5. In a heating device of the character described, a radiator structure for containing a heat absorbing fluid, said structure including a base and a header and tubes connecting said base and header and establishing communication between the same for circulation of the fluid, heating elements of substantially elongated U-shape having their arms extending through adjacent tubes and spaced therefrom to permit free flow of the fluid through said tubes, and circulating tubes between the tubes receiving the arms of the heating elements and establishing communication between the header and the base.

In witness whereof, we hereunto subscribe our names this 15 day of February, 1927.

JOHN S. GULLBORG.
CLARENCE S. ONGMAN.
